[57] CLAIM

The ornamental design for a hanger support hook, as shown and described.

DESCRIPTION

FIG. 1 is a side perspective view of a hanger support hook of my new design;

FIG. 2 is a side elevation view thereof;

FIG. 3 is a rear view thereof;

FIG. 4 is a front view thereof;

FIG. 5 is a side elevational view thereof opposite to the side illustrated in FIG. 2;

FIG. 6 is a top view thereof; and,

FIG. 7 is a bottom view thereof.

The broken lines immediately adjacent the hanger support hook represent the bounds of the claimed design and form no part thereof; all other broken lines are for illustrative purposes only and also form no part of the claimed design.
